(57) **CLAIM**

The ornamental design for a closure, as shown and described.

DESCRIPTION

FIG. 1 is an isometric view taken from the top, front, and right side view of a closure.

FIG. 2 is another isometric view thereof rotated from the view shown in FIG. 1;

FIG. 3 is a top plan view thereof;

FIG. 4 is a front elevational view thereof;

FIG. 5 is a rear elevational view thereof; and,

FIG. 6 is a left side elevational view thereof, the right side elevational view thereof being a mirror image.

In the drawings, the broken lines depict environmental subject matter only and form no part of the claimed design.
